GREASE DISPENSING APPARATUS

Robert M. Bagley, Haddonfield, N. J., assignor to
 R. M. Hollingshead Corporation, Camden,
 N. J., a corporation of New Jersey

Application January 6, 1934, Serial No. 705,562
 Renewed October 11, 1937

24 Claims. (Cl. 221—47.3)

My invention relates to a certain new and useful improvement in the art of dispensing grease, and it relates more particularly to so-called "packaged" grease, that is, grease put up in relatively small containers which are sealed by the manufacturer of the grease, and from which the grease is dispensed directly into the automobile part, such as the transmission, or differential, or free-wheeling unit of the automobile.

10 The object of my invention is to provide an original container for grease and an ejector means adapted to cooperate therewith, whereby the grease may be ejected from the original container in an efficient and facile manner without 15 waste or loss of grease, and whereby the container may not again be re-filled after its original contents has been discharged.

15 The other objects, as well as the features of which my invention consists will appear more 20 fully from the following detailed description and from the drawings accompanying the same.

25 For the purpose of illustrating my invention, I have shown in the accompanying drawings, forms thereof which are at present preferred by me, 30 since the same have been found in practice to give satisfactory and reliable results, although it is to be understood that the various instrumentalities of which my invention consists can be variously arranged and organized and that the invention is not limited to the precise arrangement and organization of the instrumentalities as herein shown and described.

35 Referring to the drawings in which like reference characters indicate like parts:

Figure 1 represents a side elevational view, 40 partly in section, showing a device embodying my invention.

Figure 2 represents a section generally on line 2—2 of Figure 1.

Figure 2—a represents a sectional view on line 2—a—2—a of Figure 1.

Figure 3 represents a section generally on line 3—3 of Figure 1.

Figure 4 represents an end view of the can gripper and grease expeller with the can removed.

Figure 5 represents a perspective view of the can seal.

Figure 6 represents a sectional view of the bottom of a can of a modified form of construction embodying my invention.

Figure 7 represents a longitudinal sectional view of a can gripper and expeller, and a can held thereby, showing a modified embodiment of my invention.

Figure 8 represents a plan view of the handle

of the ejector shown in Figure 7, with the outer washer partly broken away so as to expose to view the one-way clutch within the handle.

Figure 9 is a plan view of the metal follower plate or piston-like member shown in Figure 7. 5

Figure 10 is a sectional view of a non-metallic packing disc or follower member similar to that shown in Figure 7, but of a somewhat modified construction.

Figure 11 represents a partially sectioned view 10 of a modified form of device embodying my invention.

Figure 12 represents a fragmentary sectional view of a construction similar to that shown in Figure 1 in which frictional engagement is provided between the operating lever and the ram rod. 15

Figure 13 represents a sectional view similar to that shown in Figure 1 of a further modified embodiment of the present invention. 20

Figure 14 represents a fragmentary side elevational view of the same.

Figure 15 represents a bottom plan view of the same.

According to my invention, I provide an original 25 sheet metal container or can 15 of any suitable cross-section, but preferably of a generally cylindrical formation, as indicated in Figure 1, including the side wall 16, the end member 17 permanently fastened thereto by any conventional 30 means, as for instance the turned seam 18, and including a bottom end or flange member 19, also permanently fastened thereto by the seam 20. Merely for convenience in illustration, the seam 18 and the seam 20 have been shown somewhat 35 enlarged and disproportionate. It will be understood that the wall thickness of both side wall 16 and end members 17 and 19, is less than what is actually shown in the drawings, so that the seams 18 and 20 are correspondingly smaller in actual 40 practice. 45

The bottom end member is provided with a central opening 21 which is surrounded by an outwardly projecting and more or less cylindrical flange 22. Within the can, a sheet metal sealing member or bottom-forming plug 23 is provided, including a generally cylindrical portion 24 having a closed inner end 25, and including also a laterally extending portion 26, a more or less cylindrical portion 27 which is adapted to fit snugly within and to be frictionally retained within the flanged opening 21 in the bottom of the can, and the laterally extending flange 28, which serves to abut against the flat portion of the bot- 50 55

tom end member 19 when the plug 23 is in place, as indicated particularly in Figure 1.

When the bottom-forming plug member 23 is thus in place and frictionally gripped within the flanged opening 21 of the bottom of the can, it serves as a removable seal for said bottom opening, but is removable from the flanged opening 21 only in an inward direction indicated by the arrow 29.

10 Within the can, a follower disc or piston-like member 30 is provided, preferably of sheet metal or the like, having an annular flange 31, which is adapted more or less snugly or loosely to fit within the cylindrical wall 16 of the can, so that 15 any movement of the follower disc or piston-like member 30 in the direction of the arrow 29 will force the contents of the can also in the direction of the arrow 29 without leaving behind any appreciable amount of the material. The 20 follower disc or piston-like member 30 (in the embodiment of the invention shown in Figure 1) is provided with a socket-like recess 32, disposed centrally with respect to the disc, which may have a closed end 33, or which may be open at 25 its inner end, thereby merely leaving an annular inwardly extending flange to surround the inwardly projecting portion 24 of the bottom-forming plug 23. Either the plug 23 per se, or the piston 30 and associated plug 23 jointly, may be 30 considered to constitute a bottom portion which coacts with the end portion 19 to form a composite bottom for the container.

The top end member 17 of the container 15 is preferably provided with a screw-threaded neck 34, which may be fastened thereto by any suitable means, as for instance, by soldering at 35, or by other suitable means known in the can-making art. The screw-neck 34 is adapted to receive a corresponding screw-cap 36 having any 40 suitable sealing gasket 37 therein, for effecting a grease-proof seal.

The can is assembled with the plug 23 in place, as indicated in Figure 1, and with the follower member 30 in its bottom-most position, also indicated generally in Figure 1, and with the screw-cap 36 removed. The can is then filled with a predetermined amount of grease, of the particular grade and kind desired, and the screw-cap 36 then applied tightly to the screw-neck 34, thereby to form a grease-proof seal. Thereafter, the sealing member shown in Figure 5, and designated generally by the numeral 38 is superimposed upon the screw-cap with its depending leg portions 39 soldered to the end member 17 as at 50

55 40. Because of the slight downwardly depending annular flange 41, which surrounds the end of the screw-cap 36, and also because of the soldered relationship between the depending leg portions 39 and the end member 17, the screw-cap 36 cannot be removed without first removing the seal 38. The seal 38 is removed by breaking the soldered joints 40.

60 The ejector 42 adapted generally to coact with the container 15, includes a can gripper portion 65 and a ram-rod and actuating means therefor in operative relation to the can gripper portion. Thus, a base plate 43 or an equivalent structure is provided, including the stationary bead-engaging member 44, of more or less arcuate shape 70 and integrally or otherwise fixedly related to the base or equivalent structural member 43, and a movable bead-engaging member 45 at a point more or less diametrically opposite to the bead-engaging member 44. The movable bead-engaging member 45 may be pivoted at 46 to any suit-

able webbing or other structural member 47 integrally or otherwise fixedly related to the member 43, and yieldably held in an engaging position by any suitable spring 48.

5 The members 44 and 45 are adapted to engage the slight annular bead-like seam 20 surrounding the bottom end of the can, thereby to hold the can fast and in predetermined relation to the ram-rod 49, which extends through the member 43 at generally a right angle thereto, and 10 hence, in generally axial alignment with the can 15. In the embodiment of my invention shown particularly in Figure 1, the ram-rod is provided with a series of spaced annular grooves 15 50 throughout its length, with the exception of the innermost terminal portion thereof, which is adapted to project into and contact with the plug member 23.

10 The annular grooves 50 include the more or less plane annular surfaces 51 generally at a 20 right angle to the rod axis and the inclined and more or less conical surfaces 52, so as to form in effect, a rack which may be advanced positively by means of the spring-tensioned pawl 53, regardless however, of any rotation of the rod itself. 25 The rod 49 is slidably mounted within a suitable bore 54 of the guide member 55, which is also preferably integrally or otherwise fixedly related to the member 43 which carries the bead-engaging members 44 and 45.

30 A stationary handle 56 is fixedly secured to the member 43 by riveting or otherwise fastening it to the web 47, as at points 57. If desired, the handle 56 may be also formed integrally with the web 47 and hence, with the member 43 which 35 carries the bead-engaging members 44 and 45. The handle 56 is preferably of a slightly dished cross-section as indicated in Figure 3, and extends along the ram-rod 49, and tends to protect the same against injury in handling and operation of the ejector.

40 The movable handle 58 is preferably pivoted to the member 43, as for instance, by means of the pivot 59 extending through said handle 58 and through the pivotal lug or hinge member 60, which is also integrally or otherwise fixedly or stationarily related to the member 43, and hence, to the bead-engaging members 44 and 45. In suitable spaced relation to the pivot point 59, a hole or other suitable recess 61 is provided in the handle 58, for slidably receiving the pawl 53. 45 The pawl 53 is provided with an extension rod 62, which is preferably screw-threadedly secured thereto, which extends through the handle and terminates in the knob 63. The knob 63 includes 50 a lateral pin or similar lateral projection 64 which slides in suitable slots, and which, when raised clear of said slots and disposed transversely, will keep the pawl 53 in a retracted and inoperative position in relation to the ram rod 49. 55 The spring 65 acts upon the pawl 53 to maintain it in resilient contact with the ram rod 49 when the transverse lug or pin 64 is not so disposed as to keep the pawl in the retracted position.

60 Any suitable spring, such as the spring 66, tends 65 to displace the handle 58 in the opening direction indicated by the arrow 67.

In the normal use of the device of my present invention, the seal 38 is removed from the can and the screw-cap 36 also removed therefrom, 70 and the can held in operative position between the bead-engaging members 44 and 45, as shown in Figure 1. Thereupon, the device is gripped in one hand in the manner in which pliers are generally gripped, and the handle 58 pressed towards 75

the handle 56 repeatedly, thereby causing the ram-rod 49 to be advanced in the direction of the arrow 29. The first advance causes the dislodgment of the plug 23 from its frictional engagement with the flanged opening 21 in the bottom of the can, while a further advancement moves the plug 23 and the piston-like follower member 30 in the direction of the arrow 29, thereby to expel the contents of the can. This 10 operation may be continued until the entire contents has been displaced, whereupon the empty can is removed from between the bead-engaging members 44 and 45, and is discarded, as it cannot be thereafter re-filled. The insertion and removal of the can is effected by depressing the handle-like portion 68 of the member 45 in the direction of the arrow 69.

If desired, a discharge spout, such as illustrated particularly in Figure 7, may be screw-threadedly affixed to the screw-threaded neck 34 of the can 15 during the discharge operation. This spout is particularly desirable where it is desired to expel and dispense the grease into some more or less inaccessible or inconveniently located opening, as for instance, the re-fill opening of the transmission, differential, or free-wheeling units of an automobile.

In Figure 6, I have illustrated a modified form of container construction embodying my invention, wherein the plug and follower piston are made integrally with each other thus jointly constituting a bottom portion cooperating with the end portion 19. Thus, in this modified embodiment of follower piston construction, the plug 23 and piston 30 are formed in continuation of each other.

While in the particular embodiment of my invention shown in Figure 1, the ram-rod 49 is shown provided with tooth-like recesses, for positive engagement by a pawl, it is to be understood that the engagement between the movable handle and the ram-rod may be of a frictional character, instead of as the positive character shown. Thus, by providing a smooth ram-rod, and surrounding it by a friction gripping member, the aperture of which is slightly greater than the diameter of the rod, the rod may be advanced in the direction of the arrow 29, by causing the handle 58 to push the friction gripping member off-center, in the direction of the arrow 29, thereby "cocking" or inclining said friction gripping member in relation to the ram-rod, and causing frictional engagement between the two. Any suitable spring may then be provided for returning the friction gripping member to its initial position. By placing the spring more or less coaxially with relation to the aperture in the friction gripping member, the latter may be returned to its original position without any frictional engagement with the ram-rod.

In Figure 7, I have illustrated a modified embodiment of my invention, wherein the ram-rod 70, is provided with a coarse pitch or a multi-pitch screw 71, which is threaded through a correspondingly and internally screw-threaded bushing 72, disposed coaxially with respect to the member 43.

In this embodiment of my invention, the ram-rod is advanced by means of a handle 73 which 70 may be fixedly or otherwise secured to the outer end of the ram-rod 70. In the particular embodiment of the invention shown in Figure 7, the handle 73 is so mounted upon the outer end 74 of the ram-rod 70, as to rotate freely with respect 75 to the ram-rod in one direction, and frictionally to

grip the ram-rod when rotated in the opposite direction. Thus, to the end 74 of the ram-rod 70, a sleeve-like bushing 75 is secured (against rotation) by means of any suitable locking pin 76. The bushing 75 is provided with a lateral flange 5 77. The handle 73 is provided with a central opening 78, of generally the same diameter as the outer diameter of the bushing 75, and immediately adjacent said opening, is also provided with a pair of roller chambers 79, in diametrically opposite relation to each other. The chambers 79 have outer inclined or eccentric camming surfaces 80. A roller 81 is interposed between the surface 80 and the cylindrical surface of the bushing 75, and is yieldably urged in the direction 15 of the intended rotation of the ram-rod, to wit, in the direction of the arrow 82, by means of the springs 83, acting through suitable roller-engaging blocks 84. The cover plate 85 held in place by the screw 86, serves to hold the handle and 20 rollers in assembled relation to each other, and to the ram-rod. Thus, by rotating the handle in the direction of the arrow 87, the screw-threaded ram-rod is caused to rotate in a direction which will urge said rod forwardly in the direction of 25 the arrow 29. When rotating the handle in the opposite direction (arrow 82) the handle is moved independently of the ram-rod. By this means, the ram-rod may be advanced by repeated oscillations of the handle, without the necessity of 30 taking a new grip on the handle with each operation.

The contact end of the ram-rod 70, is preferably devoid of the screw-threads 71 and the bushings 72 or equivalent member, is preferably recessed as at 88, for a depth sufficient to receive the thread-free contact end of the ram-rod 70, so that the ram-rod may be retracted completely, or at least to a point where it is fully receded from the plug or follower member. Because of the 40 great inclination of the thread 71, the ram-rod may be moved back to its initial or outer position merely by pushing it through the bushing in a direction opposite to the arrow 29.

Any suitably curved or straight spout 89, of 45 any desired length, may be provided, having a screw-threaded coupling member 90 at one end thereof, adapted threadedly to engage the screw-threaded neck 34 of the can 15. Any suitable sealing gasket or washer 91 may also be provided 50 within the coupling member 90 for effecting a seal during the discharging operation. The nozzle or spout 89 may be of any suitable piece of tubing which is extended through a corresponding opening 92 in the coupling member 90 and is soldered 55 in place as at 93 and 94.

In Figures 7, 9, 10 and 11, I have also illustrated modified forms of follower members or piston members. In one of these modified embodiments of my invention, the metallic follower plate 95 is 60 provided with an aperture 96, preferably slightly flared in the direction of the arrow 29, and adapted snugly to fit over the cylindrical portion 24 of the bottom-forming plug 23. If desired, the follower plate 95 may also be provided with 65 the annular flange 31 similar to that indicated in Figures 1 and 6. In this embodiment of the invention however, I may also provide a suitable number of spaced radial flutes in the sheet metal plate 95 thereby to give greater rigidity to the 70 plate. The plate is preferably also slightly dished as indicated in Figure 7.

In addition to the metallic plate 95 or the metallic plate 30 (either one), I may also provide a non-metallic packing disc which may be 75

- in the form of a sheet of cardboard, or may be a cardboard center 98, having a relatively thin and more or less grease-resistant sheets of paper or similar material 99 and 100 on either side thereof.
- 5 A metallic retainer plate 101 having a central aperture 102 fitting snugly over the member 24 of the plug 23, serves to hold the packing disc in assembled relation to the piston-like member 95 (or 30) and the plug 23. The non-metallic packing disc, consisting either of the sheet of cardboard 98, or a piece of cardboard 98 flanked on either one or both sides by a sheet of more or less firm and more or less grease-resistant cheap material such as 99 and 100, is fitted snugly within 10 the cylindrical shell 16 of the can 15, so that more complete removal of the grease is made possible. Thus, by this non-metallic packing disc, a more accurate contact is obtainable between the piston assemblage and the cylindrical wall of the can.
- 15 In Figure 7, the annular flange 31 of the metallic follower plate 95 is shown slightly spaced from the cylindrical wall of the can. The clearance shown in the drawings is probably excessive and greater than the actual clearance supplied, but it will be understood that this excessive clearance shown in the drawings is merely for purposes of illustration, that is, to show that the non-metallic packing disc fits the cylindrical wall of the can more snugly and more accurately than the metallic 20 follower plate. In this case, the metallic follower plate serves more or less as a guiding member.
- In Figure 10, a further modified form of construction is shown for the non-metallic packing disc, wherein the leading side of the assemblage is provided with an upwardly flared or flanged portion 103, which, being formed of more or less pliable though initially form-retaining material, such as a piece of varnished paper, waxed paper, or otherwise treated paper, or similar fibrous material, serves to effect a more complete seal between piston assemblage and cylinder wall during the expelling operation, and is then crushed flat against the upper terminal member 17 of the can when the piston has been forced to the limit. 25
- 40 In this manner, a more efficient seal is effected during the major portion of the expelling operation, without however, interfering with the limit of movement of the piston. Thus, while the flange 103 formed of paper or other similar material, is sufficiently form-retaining to have the effect of a cup-washer, with the pressure of the contents tending to force it against the cylinder wall, yet it is sufficiently flexible to be crushed and flattened out against the end of the can so 30 that the last bit of grease may also be expelled from the can.
- In Figure 11, a further modified form of piston unit is shown, in which a cup-shaped paper disc 105 is used alone, in conjunction with a metallic follower plate, such as the follower plate 95 or 30. Thus, a suitably form-retaining paper or other fibrous material may be provided in a generally cup-shape having the flange 103, which will be forced against the cylinder wall by any slight 35 grease pressure while the grease is being expelled, and which will at the same time, be flattened out and crushed against the end of the can during the last portion of the stroke of the piston, so that the last bit of grease may also be expelled.
- 40 While the follower plates 30 and 95 may be slightly dished, as indicated in Figures 7 and 11, the force of the ram-rod will flatten out this slight concavity during the last portion of the stroke, when the edge of the follower plate is abutting 45 the end of the can, thereby giving the maximum

displacement of grease. Furthermore, by virtue of the dished follower plate illustrated in Figure 7, the combined forward force of the ramrod and the resistive forces exerted by the body of grease will slightly flatten out the slight concavity and thus will slightly increase the diameter of the dished piston and thereby compressively urge the peripheral edge of the packing (which packing is in substantial edge-wise contact with the cylindrical body wall as distinguished from the side-wise contact which would be present were the packing provided with a cup-washer-forming peripheral flange) into closer edge-wise contact with the cylindrical body wall.

While in Figures 1 and 7, the can is shown gripped at its bottom seam 20, I may also effect an engagement between the can and the ejecting means at the upper seam 18, as shown particularly in Figure 11.

It should be understood that one of the principal objects of my present invention is to provide means whereby original containers of grease may be emptied directly into the point of ultimate use, by expelling means cooperating with the can, and whereby cans of varying length may be used in conjunction with the same expelling member. Thus, it is my plan to provide a series of different sized cans, as for instance, a one-pound can, two-pound can, three-pound can, et cetera having the same diameter but varying in length according to the contents or volumetric capacity desired, and to provide expelling means which will effectively coact with the different lengths of cans, by engaging the bottom or upper 50 seams.

Hence, in Figure 11, I have illustrated a modified embodiment of my invention by which cans of varying lengths (though of the same diameter) may be engaged at their upper seams 18, by means of a plurality of adjustable bead-engaging members 110, having overhanging claw-like members 111, and being slidably mounted within guide members 112, pivoted at points 113 with suitable lugs 114 which are integrally or otherwise fixedly related to the base member 43. The springs 48 tend to deflect the guides 112 and hence the members 110 in an engaging direction. The members 110 are preferably provided with a series of teeth along their outer or inner surfaces designated generally by the numeral 115, which are adapted to be engaged by the pawl 116, yieldably pressed into contact therewith by the spring 117. The pin 118 extending transversely through the rod-like extension 119 of the pawl 116, is adapted to slide in and out in a slot 120 of sufficient depth to permit the pawl 116 to engage the teeth 115. A pair of shallower recesses 121 are also provided at a right angle to the slot 120, for receiving the pin 118 when it is desired to retain the pawl 116 in a retracted and inoperative position. This may be effected by pulling out the knob 122, and turning the knob ninety degrees.

In applying the can 15 to the expeller shown in Figure 11, the can is put in place and the gripping members 110 are adjusted by being moved in the direction of the arrow 123, until engagement is effected between the claw-like members 111 and the seam 18 of the can. In this position, the pawl retains the members 110 in place, and the grease may then be expelled by the operation of the handle 124. The handle 124 is similar to the handle 73, except it is provided with an annular rim 125.

It will be understood that the various modifications shown in the various elements of the present invention, can be variously related to each other. Thus, I may use any one of the forms 5 of piston and follower plate construction shown in these drawings, with any one of the ejecting means. Similarly, for instance, I may use the ratchet type ram-rod 49, or the frictionally engaged ram-rod in place of the screw-threaded 10 ram rod in either one of the embodiments of the invention.

Similarly, while in Figures 1 and 7, I have shown one stationary and one movable bead-engaging member (44 and 45), I may provide a plurality of movable bead-engaging members 15 similar to the member 45, in place of the stationary member 44. So too, in the embodiment shown in Figure 11, I may provide one or more of the guides 112 in fixed relation to the member 20 43 instead of in pivotal relation thereto.

In the embodiment of my invention shown in Figure 12, the ram rod 126 is surrounded at one point by a friction plate 127 having an aperture 128 therein slightly larger than the diameter of 25 the ram rod 126, and being adapted to be engaged at any suitable point, as for instance, at 129, off-center with respect to the hole 128, by means of the operating lever 58 which is pivoted at 59 in a manner similar to that shown in Figure 1. The spring 130 tends to return the friction plate 127 to its initial position with frictional engagement between it and the rod 128. The spring 130 also tends to turn the handle 58 into its open position. While in Figure 12, it is 30 not shown, it is intended to provide a spring similar to the spring 66 in the embodiment shown in Figure 1, in order that the handle 58 may be more positively returned to its open or initial position. In other respects, the member 43 is 35 similar to the member 43 shown in Figure 1, except that a deep recess 131 is provided for receiving the free end of the ram rod 126 together with the stop pin 132, so that the ram rod and the stop pin may be completely retracted. 40 In Figure 12, I have also shown the member 43 of a substantially greater depth or transverse dimension.

In Figure 13, I have illustrated certain other features of my present invention, in which the 50 ram rod 49 is engaged by a pivoted pawl 133, carried upon a pivot 134 by the handle 58. The pawl 133 is yieldably urged towards the ram rod 49 by a suitable helical spring 135, while the set screw 136 adjusts the limiting position of the 55 pawl 133 in relation to the handle 58. Thus, when the handle 58 is in the completely retracted position, deflected in the direction of the arrow 137, the pawl 133 will be clear of the rod 49, so that the rod 49 may be moved backward. The 60 spring 138 serves to open the handle 58. The spring pressed plunger 139, urged by the spring 140, serves yieldably to retain the rod 49 in any position.

It will be understood that I may interchange 65 the alternative features of one form of construction for the corresponding features of another form of construction shown in these drawings, although I have not in the drawings illustrated all such possible constructions with these elements interchanged.

I am aware that my invention may be embodied 70 in other specific forms without departing from the spirit or essential attributes thereof, and I therefore desire the present embodiments to be 75 considered in all respects as illustrative and not

restrictive, reference being had to the appended claims rather than to the foregoing description to indicate the scope of the invention.

Having thus described my invention, what I hereby claim as new and desire to secure by Letters Patent is:

1. Grease dispensing apparatus comprising an original grease container having a generally cylindrical body and having end-openings at its opposite ends, closure means closing the upper end-opening, inwardly movable but non-removable closure means associated with the bottom end-opening, said latter closure means including two separate annular portions, one a generally cylindrical flange-like annular portion for frictionally gripping and sealing with the bottom end-opening while the container is in storage or transit and prior to actual use, and the other an annular portion for engagement with the cylindrical side-wall of the container during operative inward movement of said closure means, said latter closure means being adapted to be moved out of sealing relation to the bottom end-opening and to be moved inwardly in operative relation to the side-wall of the container to dispense the grease of the container in the direction of the upper end thereof, and an annular flange member parallel with said first-mentioned annular portion of said inwardly movable closure means, said last-mentioned annular flange member defining said bottom end-opening and being adapted to grip said inwardly movable closure means through mutual engagement of said two parallel and generally cylindrical flanged portions over an annular zone of substantial axial extent.

2. Grease dispensing apparatus comprising an original grease container having a generally cylindrical body and having end-openings at its opposite ends, closure means closing the upper end-opening, inwardly movable but non-removable closure means associated with the bottom end-opening in frictionally gripped and sealed relation while the container is in storage or transit, said latter closure means including two separate annular portions, one for frictional gripping and sealing engagement with the bottom end-opening while the container is in storage or transit and prior to actual use, and the other for engagement with the cylindrical side-wall of the container during operative inward movement of said closure means, said latter closure means being adapted to be moved out of sealed relation to the bottom end-opening and to be moved inwardly in operative relation to the cylindrical side-wall of the container, to displace the grease content of the container in the direction of the upper end-opening, and manually operable ejector means adapted detachably to engage an end of said container and to advance said inwardly movable means in the direction of the upper end-opening; said ejector means including means adapted to extend through said bottom end-opening of the container.

3. Grease dispensing apparatus including the combination with an original grease package comprising a can having a sheet metal bottom member capable of having a portion thereof moved inwardly, said bottom member being permanently secured to the side-wall of the can by means of an inter-folded and inter-locking peripheral seam at the terminal of the side-wall of the can, said seam projecting laterally to a slight extent at said terminal and constituting a peripheral bead at the bottom end of the can, of ejecting means adapted to cooperate with said can, said

ejecting means including a plurality of bead-engaging means movable with relation to each other and adapted detachably to interlock with and engage said peripheral bead of said can, a ram rod carried by said ejecting means and slidably mounted generally at a right angle to the plane of said bead-engaging means, said ram rod being located generally coaxially with respect to the effective circle of said bead-engaging means, and 10 means for intermittently advancing said ram rod to move inwardly a portion of said bottom member.

4. Grease dispensing apparatus including the combination with an original grease package comprising a can having a sheet metal bottom member capable of having a portion thereof moved inwardly, said bottom member being permanently secured to the side wall of the can by means of an inter-folded and inter-locking peripheral seam 15 at the terminal of the side wall of the can projecting laterally to a slight extent at said terminal, and constituting a peripheral bead at the bottom end of the can, of ejecting means adapted to cooperate with said can, including a plurality 20 of bead-engaging means movable with relation to each other and adapted detachably to interlock with and engage said terminal bead of said can, a ram rod carried by said ejecting means and slidably mounted generally at a right angle to the plane of said bead-engaging means and being located generally coaxially with respect to the effective circle of said bead-engaging means, and means for intermittently advancing said ram rod, said ram rod advancing means having means 25 whereby it may be free from the ram rod independently of said advancing means by longitudinal force exerted directly upon the ram rod, to move inwardly a portion of said bottom member.

5. Grease dispensing apparatus including the combination with an original grease package comprising a can having a sheet metal bottom member capable of having a portion thereof moved inwardly, said bottom member being permanently secured to the side-wall of the can by means of an inter-folded and inter-locking peripheral seam 40 at the terminal of the side-wall of the can, said seam projecting laterally to a slight extent at said terminal and constituting a peripheral bead at the bottom end of the can, of ejecting means adapted to cooperate with said can, said ejecting means including bead-engaging means adapted detachably to interlock with and engage said peripheral bead of said can, a ram rod carried by said ejecting means and slidably mounted generally at a right angle to the plane of said bead-engaging means, said ram rod being located generally coaxially with respect to the effective circle of said bead-engaging means, and manually operable means movable in 45 a direction generally transversely of said ram rod for intermittently advancing said ram rod to move inwardly a portion of said bottom member, said manually operable means being adapted for operation by one hand.

6. Grease dispensing apparatus comprising an original grease container having a generally cylindrical body and end-openings at its opposite ends, a movable head portion originally gripped in the bottom end-opening of said container in 50 sealed relation thereto, said head portion having a central inwardly projecting socket, and means adapted to engage said container independently of the end wall thereof and further adapted to cooperate with said head portion to expel grease 55 from the container, said means including a ram

rod adapted to enter said socket, and means for forcing said ram rod longitudinally of said container to move said head portion inwardly.

7. In grease dispensing apparatus, a grease container having a grease expelling piston element originally associated with the bottom thereof, means for moving said grease expelling piston, said means comprising in combination a pivoted handle, means for attaching said handle to the bottom of said grease container in a position generally parallel to the axis of the container, a pawl mounted on said handle in a position substantially transverse thereto, a spring for projecting said pawl, a rod fixed to said pawl and extending through said handle to the side thereof opposite the one having the active portion of the pawl thereon, a transverse pin on said rod near the end thereof removed from said pawl, said handle having a slot therein in which said pin lies, and means whereby said pawl may be disabled by pulling said rod to withdraw said pin from its slot and turning the pin to hold the pawl in withdrawn position.

8. Grease dispensing apparatus comprising an original grease container having a side-wall and 25 having end-walls permanently affixed thereto and having an end opening in each of its opposite end-walls, means adjacent the bottom end-wall of said container and adapted for quick detachable and attachable engagement with said container independently of said bottom end-wall, said means including a plunger to expel grease from said container, and a fixed handle and a pivoted handle extending generally parallel to the axis of the container and lying generally 30 within the projected area of the bottom end-wall of the container; the outer end of said fixed handle lying generally adjacent to the axis of the container, extended, to promote grasping of both handles by one hand.

9. Grease dispensing apparatus comprising an original grease container having a generally cylindrical body, a top permanently secured to said body at one end, an annular peripheral flange secured to the other end of the cylindrical body 45 by means of any suitable annular seam, said annular flange including a short and more or less cylindrical portion, and a bottom disposed within said body and within said flange portion and having a short generally U-shaped annular reinforcement including a more or less cylindrical portion parallel to said cylindrical portion of the aforesaid annular flange and adapted to grip said annular flange through engagement of the two parallel and generally cylindrical portions over 50 an annular zone of substantial axial extent.

10. Grease dispensing apparatus comprising an original grease container having a generally cylindrical body, a top permanently secured to said body at one end, an annular peripheral flange secured to the other end of the cylindrical body by means of any suitable annular seam, said annular flange including a short and more or less cylindrical portion, a bottom disposed within said body and within said flange portion and having a short generally U-shaped annular reinforcement including a more or less cylindrical portion parallel to said cylindrical portion of the aforesaid annular flange and adapted to grip said annular flange through engagement of the two parallel and generally cylindrical portions over 60 an annular zone of substantial axial extent, and a packing disc generally adjacent the bottom and disposed inwardly of the same with its periphery 65

in generally sealing contact with said cylindrical body.

11. Grease dispensing apparatus comprising an original grease container having a generally cylindrical body, a top permanently secured to said body at one end, an annular peripheral flange secured to the other end of the cylindrical body by means of any suitable annular seam, said annular flange including a short and more or less cylindrical portion, a bottom disposed within said body and within said flange portion and having a short generally U-shaped annular reinforcement including a more or less cylindrical portion parallel to said cylindrical portion of the aforesaid 15 annular flange and adapted to grip said annular flange through engagement of the two parallel and generally cylindrical portions over an annular zone of substantial axial extent, and an expansive packing ring, carried by said bottom, in contact with said cylindrical body.

12. Grease dispensing apparatus comprising an original grease container having a generally cylindrical body, a bottom portion forming with said body a lapped seam projecting laterally of the body at the bottom end thereof, a second bottom portion frictionally held in one end of the cylindrical body, a top permanently secured to said body at the other end; said second bottom portion being capable of displacement inwardly of the body but being incapable of removal from the body, a discharge opening in said top, readily detachable and attachable claw-like gripping means adapted to engage said seam of said container, a plunger carried by said gripping means 30 in generally axial alignment with said container, and manually operable means for advancing said plunger to displace said second bottom portion towards the opposite end of the body of the container.

13. Grease dispensing apparatus comprising an original grease container having a generally cylindrical body, a bottom portion forming with said body a lapped seam projecting laterally of the body at the bottom end thereof, a second bottom portion frictionally held in one end of the cylindrical body, a top permanently secured to said body at the other end; said second bottom portion being capable of displacement inwardly of the body but being incapable of removal from the body, a packing disc disposed in generally adjacent relation to said second bottom portion, with its periphery contacting the inner cylindrical wall of the body, a discharge opening in said top, readily detachable and attachable claw-like gripping means adapted to engage said seam, a plunger carried by said gripping means in generally axial alignment with said container, and manually operable means for advancing said plunger to displace said second bottom portion towards the opposite end of the body of the container.

14. Grease dispensing apparatus comprising an original grease container having a generally cylindrical body, a bottom portion forming with said body a lapped seam projecting laterally of the body at the bottom end thereof, a second bottom portion frictionally held in one end of the cylindrical body, a top permanently secured to said body at the other end; said second bottom portion being capable of displacement inwardly of the body but being incapable of removal from the body, an expansive packing ring carried by said second bottom portion around its periphery in contact with the inner cylindrical surface of said body, readily detachable and attachable claw-like

gripping means adapted to engage said seam, a plunger carried by said gripping means in generally axial alignment with said container, and manually operable means for advancing said plunger to displace said second bottom portion towards the opposite end of the body of the container.

15. Grease dispensing apparatus comprising an original grease container having a generally cylindrical body, a top permanently secured to said body at one end, an annular peripheral flange secured to the other end of the cylindrical body by means of any suitable annular seam, said annular flange including a short and more or less cylindrical portion, a bottom disposed within said body and within said flange portion and having a short generally U-shaped annular reinforcement including a more or less cylindrical portion parallel to said cylindrical portion of the aforesaid annular flange and adapted to grip said annular flange through engagement of the two parallel and generally cylindrical portions over an annular zone of substantial axial extent, readily detachable and attachable claw-like gripping means adapted to engage one end of said container, a plunger carried by said gripping means in generally axial alignment with said container, and manually operable means for advancing said plunger to displace said bottom towards the opposite end of the body of the container.

16. Grease dispensing apparatus comprising an original grease container having a generally cylindrical body, a top permanently secured to said body at one end, an annular peripheral flange secured to the other end of the cylindrical body by means of any suitable annular seam, said annular flange including a short and more or less cylindrical portion, a bottom disposed within said body and within said flange portion and having a short generally U-shaped annular reinforcement including a more or less cylindrical portion parallel to said cylindrical portion of the aforesaid annular flange and adapted to grip said annular flange through engagement of the two parallel and generally cylindrical portions over an annular zone of substantial axial extent, a packing disc generally adjacent the bottom and disposed inwardly of the same with its periphery in generally sealing contact with the cylindrical body, readily detachable and attachable claw-like gripping means adapted to engage one end of said container, a plunger carried by said gripping means in generally axial alignment with said container, and manually operable means for advancing said plunger to displace said bottom towards the opposite end of the body of the container.

17. Grease dispensing apparatus comprising an original grease container having a generally cylindrical body, a top permanently secured to said body at one end, an annular peripheral flange secured to the other end of the cylindrical body by means of any suitable annular seam, said annular flange including a short and more or less cylindrical portion, a bottom disposed within said body and within said flange portion and having a short generally U-shaped annular reinforcement including a more or less cylindrical portion parallel to said cylindrical portion of the aforesaid annular flange and adapted to grip said annular flange through engagement of the two parallel and generally cylindrical portions over an annular zone of substantial axial extent, an expansive packing ring carried by said bottom and in contact with said cylindrical body, readily detachable and attachable claw-like gripping means adapted to

engage one end of said container, a plunger carried by said gripping means in generally axial alignment with said container, and manually operable means for advancing said plunger to displace said bottom towards the opposite end of the body of the container.

18. Grease dispensing apparatus comprising an original grease container having a generally cylindrical body, a top permanently secured to said body at one end, a bottom at the other end of said body, a lapped seam, between said body and said bottom, forming an outwardly projecting peripheral bead surrounding said last mentioned end of the body, and manually operable means provided with a plurality of claw-like members for quick detachable and attachable engagement with said bead and having a member adapted to engage and displace said bottom from its initial position inwardly of the body of the container and advance it towards the other end of the container.

19. Grease dispensing apparatus comprising an original grease container having a generally cylindrical body, a top permanently secured to said body at one end, a bottom at the other end of said body, a lapped seam, between said body and said bottom, forming an outwardly projecting peripheral bead surrounding said last mentioned end of the body, and an ejector having a relatively fixed portion adapted to engage said bead and a spring pressed portion pivoted on said relatively fixed portion and adapted also to engage said bead for quick detachable and attachable engagement therewith, and manually operable means mounted on said fixed portion and having a member adapted to engage and displace said bottom from its initial position inwardly of the body of the container and advance it towards the other end of the container.

20. Grease dispensing apparatus comprising a grease reservoir having a generally cylindrical body and having a bottom portion forming with said body a lapped seam projecting laterally of the body at the bottom end thereof, a second bottom portion frictionally secured thereto and capable of being displaced only inwardly of the body from its secured position, said second bottom portion forming a fluid seal therewith when in the secured position sufficient to permit the storage, shipment, and handling of the reservoir containing grease without leakage past said seal, and forming a fluid seal with the inner surface of the cylindrical body of the reservoir when displaced inwardly from its secured position sufficient to cause the expulsion of the grease contents of the reservoir as a result of such inward displacement at the bottom, readily detachable and attachable claw-like gripping means engaging said lapped seam, a pressure plunger carried by said gripping means in general axial alignment with said container, and manually operable means movable in a direction generally transversely of said plunger and capable of advancing said plunger axially towards the reservoir, and to dislodge said second bottom portion from its frictionally secured position and to advance it through the reservoir towards the opposite end thereof.

21. In lubricant dispensing apparatus, an original container for lubricant, and constituting a vendable grease package unit, comprising a generally cylindrical body having at least one terminal member permanently affixed thereto at one end thereof, and a recessed piston of generally dished contour slidably disposed within said cylindrical body at the opposite end thereof, the peripheral

extremity of said piston being slightly spaced from the inner wall of said cylindrical body, said piston being provided with a flangeless peripherally projecting annular ring of any suitable non-metallic packing material in substantial edgewise contact with said inner wall, and said piston being adapted to receive the thrust of external piston-advancing means in the recess thereof, whereby the forward thrust of said external piston-advancing means combined with the opposed resistive forces exerted by a body of grease will tend to slightly increase the diameter of said dished piston thereby to directly compress the annular ring of packing material and urge it into closer edgewise contact with the inner wall of said cylindrical body.

22. Grease dispensing apparatus comprising an original grease container having a generally cylindrical body, a top permanently secured to said body at one end, an apertured bottom permanently secured to the other end of said cylindrical body by means of any suitable annular seam, an inwardly removable bottom closure member of a diameter substantially smaller than the overall diameter of said apertured bottom frictionally retained within said aperture, readily attachable and detachable claw-like gripping means adapted to engage said annular seam, a plunger carried by said gripping means in generally axial alignment with said container and said closure member, and operable means for advancing said plunger to displace said inwardly removable bottom closure member towards the top of said container.

23. Grease dispensing apparatus comprising a grease reservoir having a generally cylindrical body and having a bottom portion forming with said body a lapped seam projecting laterally of the body at the bottom end thereof, a second bottom portion frictionally secured thereto and capable of being displaced only inwardly of the body from its secured position, said second bottom portion forming a fluid seal therewith when in the secured position sufficient to permit the storage, shipment, and handling of the reservoir containing grease without leakage past said seal, and forming a fluid seal with the inner surface of the cylindrical body of the reservoir when displaced inwardly from its secured position sufficient to cause the expulsion of the grease contents of the reservoir as a result of such inward displacement at the bottom, readily detachable and attachable gripping means engaging said lapped seam, a pressure plunger carried by said gripping means in general axial alignment with said container, and manually operable means movable in a direction generally transversely of said plunger and capable of advancing said plunger axially towards the reservoir, and to dislodge said second bottom portion from its frictionally secured position and to advance it through the reservoir towards the opposite end thereof.

24. Grease dispensing apparatus including the combination with an original grease package comprising a can having a sheet metal bottom member capable of having a portion thereof moved inwardly, said bottom member being permanently secured to the side-wall of the can by means of an inter-folded and interlocking peripheral seam at the terminal of the side-wall of the can, said seam projecting laterally to a slight extent at said terminal and constituting a peripheral bead at the bottom end of the can, of ejecting means adapted to cooperate with said can, in-

cluding a plurality of bead-engaging means movable with relation to each other and adapted detachably to interlock with and engage said peripheral bead of said can, a ram rod carried by said ejecting means and slidably mounted generally at a right angle to the plane of said bead-engaging means, said ram rod being located generally coaxially with respect to the effective circle of said bead-engaging means, and means

for intermittently advancing said ram rod to move inwardly a portion of said bottom member, said ram rod advancing means having means whereby it may be freed from the ram rod thereby to permit the retraction of said ram rod independently of said advancing means by longitudinal force exerted directly upon the ram rod. 5

ROBERT M. BAGLEY.
